REVERSING VALVE

Haakon Hellan, Chicago, Ill.

Application April 10, 1930, Serial No. 443,090

3 Claims. (Cl. 251—51)

My invention relates to reversing valves for regenerative furnaces.

My invention relates to the control of air to and waste gas from regenerative furnaces, such as open hearths and glass tanks. It belongs to the class of valves using a damper (gate valve) sliding against a water cooled metallic seat for shutting off and opening to stack in the underground flue system, where temperatures range around 1500° F. Present practice offers dampers of different construction. Brick dampers in metal frames are porous. A solidly cast metal damper, whether in one piece or in sections, will warp and cause leaks. All-water cooled dampers of tight box construction require clean water to avoid settling out of sediments, and large quantities of the water on account of the large exposed area to the heat.

One object of my invention is to provide a damper construction that insures tightness by water cooling, but reduces water requirements to cooling of contacting parts only, and by its construction permits the use of raw water in constant circulation.

Another object is to construct the main area of the damper of a light metal plate to withstand the heat, and avoid the heat losses from excessive water cooling.

Another object is to provide an arrangement of damper and the air inlet into one vertical flue passage, principally for saving of floor space, but also to bring the inflowing cold air into intimate contact with the damper.

Another object is to provide a position of the damper in relation to the air inlet so that stack suction, weight and air pressure always will keep the damper against the seat. This object is accomplished with an air inlet valve on the regenerator side of the damper seat, this valve opening and closing the vertical air passage to regenerator flue, said passage having one side formed by the damper.

Another object is to provide a gate valve with novel cooling means comprising a metal frame approximating the size and shape of the seat and provided with a removable plate covering the frame opening.

Referring to the accompanying drawing, Fig. 1 is a vertical section of the valves and adjacent elements for one side of a regenerative furnace, parts being in elevation. Fig. 2 is a section on the line 2—2 on Fig. 1.

On the drawing, 1 is a damper adapted to the seat 2 between the regenerator flue 3 and the stack flue 4. 5 is a passage by which air is con-

ducted to the flue 3 after passing through the conduit 6 and the valve chamber 7. A vertically-reciprocating valve 8 of the saucer or cone type is adapted to close the valve seat 9 in the bottom of the chamber 7.

The seat 2 is a metal frame having therein a water cooling passage 10 provided with the inlet and outlet ducts 11 and 12. The damper comprises a metal frame 13 having substantially the shape and size of the seat 2. This frame is provided with a water cooling passage 14 having the inlet and outlet pipes 15 and 16 which slide in openings in the upper wall of the shaft or passage 5. The pipes 15 and 16 are provided with flexible hose, one marked 17 supplying the pipe 15. It will be understood that another hose like 17 is to be connected to the pipe 15. The damper 1 is inclined toward the stack flue. The upper edge of the frame 13 has attached thereto the rod 18 reciprocable through the upper wall of the port and air passage 5. This rod is connected above the air passage 5 by the rope 19 to the drum 20 on the shaft 21. On the same shaft is the smaller drum 22 provided with the rope 23 which runs over the sheave 24 which is attached to the stem 25 of the valve 8.

With the parts as shown on the drawing, air would pass down through the conduit, the valve chamber 7, the air passage 5 and the regenerator flue and thence on to the regenerator, not shown, the air contacting with the valve 1 as it enters the flue 3 whereby the valve is somewhat cooled and the air somewhat heated. From the regenerator the air having been heated thereby passes to a furnace, the waste gases passing from the furnace through a second regenerator and regenerator flue into the stack flue 4 at the opposite end of that shown on the drawing. As the connection of reversing valves to a regenerative furnace is old and well-known and as this invention relates entirely to the valve construction and arrangement, the regenerators, the furnace and the second set of valves like that shown have all been omitted. It will be readily understood that there will be at the right of Fig. 1 a second set of valves like 1 and 8 arranged to be operated so that when the damper 1 is closed and the air inlet valve 8 is open, the corresponding valves in the other valve unit will be in reverse position.

It will be noted that the damper frame 13 is provided with a cover plate 26 removably secured to the frame 13 by means of bolts 27 or equivalent devices. It will be seen that when the air which is fed under pressure passes from the passage 5

to the regenerator flue 3 it produces a pressure on the damper 1 tending to hold it more closely to its seat 2. It will also be noted that the air tends to hold the valve 8 on its seat when it is closed. The ropes 19 and 23 are wound in reverse directions on the drums 20 and 22 so that when the shaft 21 is rotated to move the valves 1 and 8 they are always moved so that one is open and the other is closed. My hollow damper frame corresponds in shape and size to the damper seat and is much better than it would be if the water cooling portion were a large chamber having substantially the area of the valve. With my frame provided with a circulating fluid the rapid movement of the water therein prevents the settling of any sediment. With a damper with a large water-cooled chamber having the same area as the damper, the circulation of water is much slower so that sediment will gradually gather and cut-off the circulation of water from at least a large portion of the damper. Thus, the frame of my damper will be preserved much longer than it would be if the water circulated through a hollow substantially the size of the damper. Should the plate 26 be burned-out it is but a small matter to supply another in its place.

I claim:—

1. In a damper construction adapted to be subjected to intense heat, a damper comprising a hollow frame member providing a passageway for a cooling medium to preserve the same from the destructive effect of heat, said frame member having an opening therethrough, and an inde-

pendent continuous thin metal cover plate completely covering said opening, separate from but mechanically attached at its edges to said frame member, whereby warping or expansion strains in the plate due to heat will not cause distortion of said cooled frame. 5

2. In a damper construction adapted to be subjected to intense heat, a damper comprising a hollow frame member providing a passageway for a cooling medium to preserve the same from 10 the destructive effect of heat, said frame member having an opening therethrough, and an independent continuous thin metal cover plate completely covering said opening, separate from but 15 removably attached at its edges to said frame member, whereby warping or expansion strains in the plate due to heat will not cause distortion of said cooled frame.

3. In a damper construction for a regenerative furnace provided with a regenerator flue and a 20 stack flue, a vertical air passage separating said flues, a damper seat with an opening registering with the stack flue, a damper adapted to rest against said seat or to be lifted in said air passage, and a main air inlet for supplying air to the 25 furnace, said inlet opening into said air passage at a point removed from said damper when raised but in a position to constitute means for directing the air flow against the side of the 30 damper away from its seat to aid substantially in holding the damper on its seat.

HAAKON HELLAN.
